UNITED STATES PATENT OFFICE.

CHARLES D. KLINE, OF CLEVELAND, OHIO.

HEADLIGHT.

1,295,905.

Specification of Letters Patent.

Patented Mar. 4, 1919.

Application filed September 10, 1918. Serial No. 253,442.

To all whom it may concern:

Be it known that I, CHARLES D. KLINE, a citizen of the United States, residing at Cleveland, in the county of Cuyahoga and State of Ohio, have invented certain new and useful Improvements in Headlights, of which the following is a specification.

The invention relates to head lights and more particularly to lamps of this nature for vehicles, principally of the motor driven type such as automobiles.

The principal object of the invention is the provision of a multi-colored head light which may indicate safety, caution, or danger, according to the accustomed code of traffic signaling by lamps or analogous light.

The invention provides a head light designed chiefly for automobiles and motor vehicles which embodies separate and independent chambers for the different lights, so that each may be maintained separate from the other and thereby avoid any possible confusion.

The invention furthermore aims to provide a head light which may also be used for throwing a side light, the body of the lamp having a lateral opening which when desired may be covered by a suitably provided door.

A further purpose of the invention is the provision of a lamp which, in an emergency, or when required, may be utilized as a trouble lamp for lighting any part of the machine when it becomes necessary to make an inspection or needed repairs, such trouble lamp preferably consisting of one of the auxiliary lamps provided for a supplemental chamber.

The drawing illustrates a preferred embodiment of the invention, however, it is to be understood that in adapting the same to meet different conditions, various changes in the form, proportion, and minor details of construction may be resorted to without departing from the nature of the invention as claimed hereinafter.

Referring to the drawings thereto attached,—

Figure 1 is a front view of a head light embodying the invention.

Fig. 2 is a side elevation of the head light.

Fig. 3 is a central longitudinal section on the line 3—3 of Fig. 1 looking in the direction of the arrows.

Fig. 4 is a transverse section on the line 4—4 of Fig. 2 looking forward as designated by the arrows.

Corresponding and like parts are referred to in the following description and indicated in the several views of the drawing by like reference characters.

In the preferable construction of the head light the body is formed in sections which are separable thus providing for ready access to the interior of the lamp as also facilitating the construction thereof. The body of the lamp comprises a front section 1 and a rear section 2, said sections having a slip joint and secured by bayonet joints 3, 70 or other suitable fastening means. The rear end of the section 2 is constructed to provide a reflector 4 in a manner well understood and receives a lamp 5 of the electric type. An opening 6 is formed in a side of the section 2 and is adapted to be closed by means of a cover 7 which is hinged to the section 2 in any well known manner and which is secured when closed by any suitable fastening means 8. A lens may be fitted in the opening 6 in any well known manner and may be of any color according to the nature of the rays of light to be thrown laterally from the lamp when the cover or door 7 is swung into open position. Wings 35 or extensions 9 project from the body of the lamp and serve as means for securing or bracing the same when in position upon the motor vehicle.

The body of the lamp flares forwardly and is closed at its front by means of a door 10 which is hinged at one side to the body of the lamp and is adapted to be fastened when closed in any well known manner. The door 10 comprises a frame and 95 a lens 11, the latter being usually of glass and secured to the frame in a way to admit of replacement.

Within the body of the lamp and at one side thereof are located similarly formed 100 chambers which are designed to project colored rays of light, such as green and red. Portions of the body of the lamp are pressed outwardly as indicated at 12, to form depressions which are closed at their inner 105 side by means of walls 13 the same consisting of pieces of sheet metal bent into proper shape and bolted or otherwise fastened to the body of the lamp as indicated at 14. The walls 12 and 13 are oppositely 110

curved and provide longitudinal chambers which open forwardly, so as to throw the rays of light in advance of the vehicle to which the lamp is fitted. The rear end of the outer walls 12 merge into the walls of the body. The rear ends of the walls 13 terminate abruptly thereby leaving spaces which are closed by means of doors 16 which are preferably hinged to the body of the lamp. The doors 16 provide for ready access to the interior of the chambers when the parts of the lamp body are separated. A lamp 15 is located in each of the light chambers and these lamps may be of any desired color according to the color of the rays of light to be projected. When the lamps 15 are clear or white the desired color may be obtained by locating colored lenses in the supplementary light chambers as will be readily understood. The lamp 5 is designated as the main lamp and the lamps 15 as the auxiliary lamps. These lamps are detachably fitted in place in any well known manner to admit of replacement. Either one of the auxiliary lamps 15 may be used as a trouble lamp when it becomes necessary to make an inspection or repairs after dark. It is to be understood that the several lamps may be included in independent circuits, so that each lamp may be separately controlled. If preferred all the lamps may be included in one circuit. These are mere matters of de-

tail which may be arranged to meet existing conditions.

The foregoing description and the drawings have reference to what may be considered the preferred, or approved, form of my invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by Letters Patent is:—

1. A head light, comprising a body formed of separable front and rear sections, the rear section containing a light and having a side opening, and a front section provided with light chambers extending partly within and partly without the wall thereof and a door common to and closing the body and chambers.

2. A head light comprising a body formed of separable front and rear sections, the front section having light chambers at one side thereof and a door at the forward end of the front section.

In testimony whereof I affix my signature in presence of two witnesses.

CHARLES D. KLINE.
